CARPET SWEEPER

Henry W. Gussack, Richmond Hill, N. Y.

Application January 22, 1937, Serial No. 121,893

12 Claims. (Cl. 15—48)

This invention relates to a new and improved carpet sweeper in which means are provided for cleaning the rotary brush or brushes.

It is an object of the invention to provide means whereby the comb or teeth acting as a cleaner for the rotary brush or brushes may themselves be effectively cleaned upon the opening or evacuation of the dust pan.

A further object of the invention is to provide means which will simultaneously actuate the comb or combs and open the dust pan.

A further object of the invention is to provide a new and improved unitary construction for the casing enclosing the carpet cleaning mechanism.

A still further feature of the invention is to make the outer casing from a single sheet of metal.

With these and other objects which will become apparent as the description proceeds, the invention is set forth in detail below, claimed in the claims and shown in the drawings, in which:

Fig. 1 is a plan view of the improved carpet sweeper.

Fig. 2 is a cross sectional view taken on the section line 2—2 of Fig. 1.

Fig. 3 is a slightly enlarged cross sectional view taken on the section line 3—3 of Fig. 2.

Fig. 4 is an enlarged view of a detail at one corner of the carpet sweeper looking upwardly, and

Fig. 5 is a partial plan view illustrating a modification.

Referring to the drawings in which similar reference characters indicate like parts, the casing of the carpet sweeper is indicated at 1. The casing comprises a unitary sheet of metal stamped into the form indicated. Secured to the outside of the casing 1 in any desired manner is the ordinary buffer elements 2.

Wheels 3 of the usual type are mounted on the shafts 4 and the shafts 4 in turn extend through the slots 5 in the transverse walls 8.

The dust pan elements 6 are in turn pivotally mounted by the pivot 7 to the transverse members 8 secured within the casing 1.

The usual rotary roller 9 fits between the wheels 3 and the handle member 10 has the side arms 11 with in-turned portions fitting within recesses provided at the ends of the rotary brush. The handle member 10 therefore provides the trunnions for the brush member 9 which is the usual construction.

Spring members 12 are provided with one end secured to the underside surface of the casing 1 and the other end secured to the shafts 4 in order

to maintain the wheels 3 in the position shown in Fig. 2. The dust pans 6 are provided with in-turned flanges 13 fitting within the recess 14 provided in a member 15 which is secured by spot welding or otherwise to the interior side 5 walls of the casing 1.

The means for fitting the dust pan so as to empty the same comprises the following: A U-shaped loop member 16 is pivotally secured to the interior edge 17 of each dust pan. Upon movement of the loop member 16 the dust pan will pivot about the pivot 7 and thereby permit the pan to be emptied. A double armed lever member 18 pivoted at 19 and having an actuating member 20 has a pivotal connection with the looped member 16 at 21 so that upon actuation of the member 20 downwardly, as shown in Fig. 2, the looped member 16 will be moved upwardly and thereby pivot both dust pans. Upon release from the action of the lever 18 the member 16 will exert a spring like action upon the dust pans to hold them in closed position.

A series of teeth 22 are provided upon the bar member 23 and extend downwardly so as to contact the bristles on the brush member 9 and clean the same. The teeth 22 and the bar member 23 constitutes a comb member. Two comb members are shown in the modification being described, but it is obvious that only one may be provided if desired or more than two.

The comb members shown more particularly in Fig. 3 of the drawings are supported with the bar member 23 on the outside of the casing 1 and with the teeth 22 preferably somewhat pointed extending downwardly into the interior of the casing. The teeth are maintained in aligned position so as to prevent any pivoting by the member 24 which is secured to the under surface of the casing 1 in any desired manner with a felt member 25 intervening. The felt member 25 is designed to closely fit against the teeth 22 and upon movement of the teeth 22 with relation to the felt member 25 effectively remove from the teeth 22 any adhering dust, dirt or fibers.

The member 24 is provided with downwardly grooved portions 26 which portions have provided therein apertures 27 for the passage of teeth 22. The grooved portions are spaced from the lower surface of the casing 1 so that the shorter movement of the teeth 22 is required for cleaning the interior surface of the teeth 22. As is obvious if the grooved portions 26 were not provided then the teeth 22 would have to be practically entirely raised out of the casing member 1 in order to clean the lower portions thereof, while with the

grooved portions 26 spaced some distance from the under surface of the casing 1, such an extreme movement is not necessary. The felt member 25 may be of any desired character and is 5 preferably a loosely woven material which will closely adhere to the sides and surface of the teeth 22.

The means for actuating the teeth 22 and 10 cleaning them comprises the following: Secured at the interior edges of each of the dust pans 6 are the links 28. The links 28 are pivotally secured to such edges in any desired manner and the upper ends 29 of the links are connected to a lug 30 integral preferably with the bar member 23 and projecting downwardly in the plane 15 of the teeth 22. As will be noted upon downward actuation of the member 20, the dust pans will be pivoted in the manner described above, and at the same time the links 28 will be raised 20 upwardly and thereby raise the bars 23 carrying with them the teeth 22 which, upon movement will be cleaned by both the apertures 27 in the metal member 24 and also the adhering felt member 25. In this manner upon actuation of the 25 dust pan, the teeth are cleaned at the same time.

Generally the teeth 22 are arranged in staggered relation as shown particularly in Fig. 4 of the drawings.

30 A modification of the invention is shown in Fig. 5 wherein instead of having two separate bars 23 as shown in the modification described above, a single bar member 31 is provided, from which one or two sets of teeth may project. The remainder of the construction in this modification is similar to that described above.

As will be noted from the above, the working parts are all assembled as a separate unit and may be installed as a single unit into the one 40 piece casing. The separate unit comprises the elements 15 with the transverse member 8 and after the casing has been properly stamped out such unit with the cleaning equipment may be easily secured to the casing.

45 As will be noted when the teeth of the combs are moved for cleaning purposes, any part which adheres thereto will be moved off and into the dust pans.

Whenever there are two or more combs they 50 may be suspended through perforations in the body independently with small narrow heads on the outside of the body, or they may issue from one master plate which lies on top of the outside surface of the sweeper in such a way as to 55 permit the teeth to extend through the perforations provided in the casing member itself towards the center sufficiently to clean the brush bristles.

I claim:

60 1. A carpet sweeper comprising a casing member, a brush located therein, brush cleaning mechanism within said casing member, a dust collector within said casing, means for emptying dust from said collector at desired intervals and 65 means on said casing for cleaning said brush cleaning mechanism operative at the same time as said emptying means.

2. A carpet sweeper comprising a casing, a rotary brush located in said casing, pivotable dust 70 pans mounted in said casing cooperating with said brush, means for cleaning said rotary brush, means for cleaning said cleaning means, and unitary means for actuating said last named cleaning means and pivoting said dust pans.

75 3. A carpet sweeper comprising a rotary brush,

5 pivotable dust pans cooperating with said brush for collecting the dirt and dust removed from cleaned surface, combs for cleaning said rotary brush, a cleaning element contacting said combs, means for reciprocating said combs with relation to said cleaning element in order to clean the same when said pans are pivoted.

4. A carpet sweeper comprising a unitary casing, a rotary brush member located therein, a dust pan pivotably mounted in said casing cooperating with said brush member, means for tilting said dust pan in order to empty the same, a comb member coacting with said brush member for cleaning the same, a cleaner for said comb member, means for reciprocating said comb member relative to said cleaner in order to clean the same, and means whereby said comb member and said dust pan may be actuated in unison.

5. A carpet sweeper comprising a casing, a rotary brush member therein, dust pans cooperating with said brush member, means for pivoting said dust pans in order to empty the same, a plurality of comb members cooperating with said brush member in order to clean said brush, and means for cleaning said comb members operative upon actuation of said dust pans.

6. A carpet sweeper comprising a unitary casing, a rotary brush located within said casing, pivotably mounted dust pans cooperating with said brush in order to collect the dirt and dust, and means for tilting said dust pans in order to empty the same, a plurality of staggered comb members extending downwardly into said brush member so as to clean the same, a unitary plate 30 associated with said casing upon which said comb members are fixed, a cleaner for said comb members and means for reciprocating said plate and thereby said comb members relative to said cleaner in order to clean said comb members in unison with said means for emptying the said dust pans.

7. A carpet sweeper comprising a unitary casing, a rotary brush member, located within said casing, combs for cleaning said brush extending from said casing into said brush member, a supporting plate for said combs secured to the under surface of said casing, a felt member adapted to coact with the teeth of said combs for cleaning said teeth secured between said supporting member and said casing and means for causing relative movement between said combs and felt member.

8. A sweeper comprising a casing, a brush therein, means for collecting the dirt and dust removed by said brush, means for evacuating said dirt and dust from said collecting means, means for cleaning said brush, means for cleaning said cleaning means for said brush and means operatively connecting said last named means and said 60 evacuating means for operating said last named means simultaneously with the operation of said means for evacuating said dirt and dust from said collecting means.

9. A sweeper comprising a casing, a brush member therein, a dust pan in said casing cooperating with said member, means for evacuating said dust pan, a comb for cleaning said brush member and manually operated means associated with said casing for cleaning said comb.

10. A sweeper comprising a casing, a brush member therein, a dust pan cooperating with said member, means for evacuating said dust pan, a comb normally engaging said brush member in fixed position for cleaning said brush member,

means engaging the teeth of said comb and manually operable means for moving said comb and said means engaging the teeth relative to one another in order to clean the teeth of said comb.

5 11. A sweeper comprising a casing, a brush member associated with said casing, a comb positioned in fixed position during the operation of said sweeper for cleaning said brush member, a member having perforations through which the 10 teeth of said comb project and means for mov-

ing said comb and said perforated member relatively to one another so as to clean the teeth of said comb.

12. A sweeper comprising a casing, a brush member associated with said casing, a comb for 5 cleaning said brush member, a felt member having perforations through which the teeth of said comb project and means for relatively moving said comb and felt member to clean said comb.

HENRY W. GUSSACK. 10
